UNITED STATES PATENT OFFICE.

AUGUST HILDT, OF NEW YORK, N. Y., ASSIGNOR TO LOUIS DRYFOOS & CO., OF SAME PLACE.

DESIGN FOR THE ORNAMENTATION OF SKIRTS, LININGS, &c.

SPECIFICATION forming part of Design No. 17,809, dated October 25, 1887.

Application filed September 5, 1887. Serial No. 248,906. Term of patent 7 years.

To all whom it may concern:

Be it known that I, AUGUST HILDT, a citizen of the United States, and a resident of the city, county, and State of New York, have invented a new and original Design for Surface Ornamentation of Skirts, Linings, and other Similar Articles, of which the following is a specification.

My design is for the surface ornamentation 10 of skirts, linings, quiltings, and similar articles; and it consists of the parallel rows of circles and the intervening lozenge-shaped figures or parallelograms arranged and disposed as will hereinafter more fully appear.

15 In the accompanying drawing I have represented in a single figure a portion (containing all the elements) of my design as it appears when applied to or upon the article or goods, dotted lines being employed to indicate stitches, 20 and these lines being arranged or grouped in accordance with my design, this illustration being deemed sufficient for purposes of this specification.

For convenience of description the various 25 parts of the design may be referred to in the following order:

A A A are circles located one above the other, or in parallel lines, of any number, and distant from each other, as will be observed, 30 about the length of a radius.

B B B are circles similar to A A A, similarly disposed and spaced, forming a parallel 35 row of circles. The two rows are separated from each other by a distance near or about five times the length of one of the radii, in order that the intervening lozenge-shaped figure may be suitably proportioned. Any 40 number of these vertical rows of circles may be added, and thus the design made to cover any desired extent of surface.

Between the circles A A and B B are straight 45 lines of stitching extending from the extremity of the horizontal diameter of one circle to corresponding points on circles in the next row, and the arrangement is such as to form a series of lozenges or parallelograms, as a b c d, touching at their angles and lying between the vertical rows of circles. These lozenges

will be varied in size by varying the distance between the circles.

The description so far indicates the general principles upon which the lines and circles are grouped.

To increase the number of lines and circles in any given space the same general arrangement is followed for the ground-work, and upon this or to this are added two series of lines and circles precisely like the first, as indicated at the upper part of the figure, wherein, for instance, a circle, as A', has its center located upon the circumference of the next circle A, and another, A'', has its center located upon the circumference of the next circle A in the series. The same arrangement is followed in each vertical row, the cross-lines 65 between all the circles drawn as before explained form a series of small lozenges, as will be readily seen, and these fill the space between the vertical rows of circles. The ground-work alone may constitute the whole design 70 in any pattern, or the triplicate thereof may be entirely employed. I prefer to employ both together, the lower part forming a heavy margin for the pattern, while the upper part appears lighter; but the upper and lower parts 75 might be reversed.

This design is to be distinguished from one in which the ground-work or base includes rows of circles tangent to each other, and also from one in which the lower or heavier part 80 shows only circles tangent and not intersecting each other, as illustrated herein.

Having now fully described my design, what I claim as new, and desire to secure by Letters Patent, is—

The design for the ornamentation of skirts, &c., consisting of the parallel rows of circles and the intervening lozenge-shaped figures or parallelograms under the arrangement, substantially as shown and described.

In testimony whereof I have hereunto set my hand.

AUG. HILDT.
